UNITED STATES PATENT OFFICE.

SIMON DEUTSCH, OF MILWAUKEE, WISCONSIN.

PATTERN-MAKER'S TOOL.

1,412,555.

Specification of Letters Patent. Patented Apr. 11, 1922.

Application filed May 18, 1920. Serial No. 382,292.

To all whom it may concern:

Be it known that I, SIMON DEUTSCH, a citizen of Hungary, and has first citizen papers of the United States, and resident of 5 Milwaukee, in the county of Milwaukee and State of Wisconsin, have invented certain new and useful Improvements in Pattern-Makers' Tools; and I do hereby declare that the following is a full, clear, and exact description thereof.

My invention has for its object to provide a simple, economical and useful marking tool which is especially designed for pattern-makers' work or the like.

15 The primary object of the invention is to provide a head for adjustable sliding connection with a marking beam, which head is provided at its ends with a plurality of work contact faces or shoes, at least one of them 20 having a straight edge, while the others of the series are provided with working faces of greater or less curvature to accommodate the tool for engagement with the edges of work, whether the edges are straight or 25 curved either internally or externally.

With the above objects in view, the invention consists in certain peculiarities of construction and combination of parts as set forth hereinafter with reference to the accompanying drawing and subsequently claimed.

In the drawing:

Figure 1 represents a side elevation of a marking beam equipped with a sliding head 35 embodying the features of my invention.

Figure 2 is a corresponding view, showing the reversed side of the head.

Figure 3 is an end view of the head with the marking beam in section as indicated 40 by the line 3—3 of Figure 1, and

Figure 4 is a side elevation of the head, showing the offset arrangement of the contact shoes.

Referring by characters to the drawing, 1 represents a marking beam which in this exemplification of the invention is shown round in cross section and 2 illustrates a marking pin that projects from one end of the beam. Slidably mounted upon the beam 45 is a head 3 in the form of a sleeve having an aperture therein which conforms to the cross sectional area of the beam and is adapted to permit the head to slide thereon, so as to vary the distance between the work surfaces 50 of said head and the marking pin. The head is held in its adjusted position by a

binding screw 4 which passes through a suitable threaded aperture in the body of the head and contacts with the surface of the beam. As best shown in Figures 1 and 2, 60 the ends of the head have offset surfaces which are adapted to abut either the external or internal edges of the body of material upon which the artisan is operating to form a pattern. These offset portions constitute 65 a series of shoes, four in number. The shoe indicated by the numeral 5, is provided with an external curved surface of a comparatively great sweep, while the shoe 6 at the opposite end of the head is of a comparatively 70 small sweep, the same being best illustrated in Figure 2. The shoe 5 is merged into a shoe 7 as best shown in Figure 2, which shoe has a straight working edge and opposite the shoe 6 the surface of the head is 75 formed into an offset working surface having a double curve as indicated by the numeral 8. The double curved surface inclines inwardly, and these curvatures meet in a line approximately radial to the center 80 of the beam. Thus this working surface or shoe presents a pair of contact faces 8', 8'' which are adapted to have sliding engagement with the curved surface of the work. For example, if it is desired to mark a line 85 concentric with an external curve, indicated by the dotted line X, the shoe 8 is employed, due to the fact that the curvature X is of quite a large sweep and being an external edge of the work when the tool is guided by 90 the shoe 8' and moved to slide along the face of the line.

Obviously the marking pin 2 will describe a line parallel to the curvature X. Should the operator desire to indicate a line upon 95 an internal circle, as indicated by the character y, due to the fact that this curve y is of comparatively large diameter, the shoe 5 is utilized as a guide surface for the tool. Hence when the tool is inserted into a circular hub aperture, as indicated at y and said tool is manipulated so as to describe a circle riding upon the shoe 5, the marking pin 2 will describe a corresponding circle outside of and concentric with the circle y. In this 100 operation the center of movement will be between the marking pin and the shoe 5.

It follows that the smaller curved surface shoe 6 can be utilized where the center aperture in the work is of a very small diameter 110 and the operation is the same as in connection with the operation just described where

the shoe 5 is utilized except that the center of movement is on the opposite side of the shoe from the marking pin.

When it is desired to use the tool for straight line work, as indicated by the dotted line z , Figure 2, the straight surface shoe 7 is utilized and the marking tool will then describe a line in connection with the pin 2 paralleling the dotted line z . Obviously owing to the adjustable feature of the head upon the beam, varying microhmic dimensions may be found between the point of the shoe and the pin 2, the selection of which shoe depends upon the nature of the work required.

While the drawing illustrates a beam circular in cross section, obviously this beam may be made rectangular or polygonal depending upon the requirements of the manufacturer, without departing from the spirit of my invention, and furthermore, the materials utilized for the beam and head may be suitably selected.

While I have shown and described one exemplification of my invention minutely as to detail, obviously the structural features may be varied within the scope of the claims.

I claim:

1. A marking-gage comprising a beam provided with a marking element at one end,

a head adjustably mounted on said beam, a shoe formed on said head and having two convex curved surfaces facing said marking element, said surfaces intersecting in a cusp which extends radially from the central line 35 of said beam whereby said convex surfaces are adapted to engage the external edge of a circle of any radius to guide the marking element in a circle concentric therewith.

2. A marking-gage comprising a beam 40 provided with a marking element at one end, a head adjustably mounted on said beam, a shoe formed on the head and having a surface thereon adapted to engage the external edge of a circle to guide the marking element in a circle concentric therewith, a second shoe at one end of the head and having a convex surface facing away from the marking end of the gage and adapted to engage the internal edge of a circle, and a third 50 shoe at the other end of the head and having a convex surface facing in the opposite direction and adapted to engage the external edge of a circle for the purpose set forth.

In testimony that I claim the foregoing I 55 have hereunto set my hand at Milwaukee, in the county of Milwaukee and State of Wisconsin.

SIMON DEUTSCH.
